DESIGN FOR A VANITY CASE

Ossip J. Walinsky, New York, N. Y.

Application January 3, 1935, Serial No. 54,695

Term of patent 3½ years

To all whom it may concern:

Be it known that I, Ossip J. Walinsky, a citizen of the United States, and resident of New York city (Borough of Manhattan), in the county and State of New York, have invented a certain new, original, and ornamental Design for Vanity Cases, of which the following is a specification, reference being had to the accompanying drawing, forming a part thereof, and of which Figure

1 is a view in front elevation in closed position, Fig. 2 is a view in end elevation; and Fig. 3 is an outside view in elevation showing my vanity case completely opened up in flat position and with one of the flaps raised, showing my new design.

I claim:

The ornamental design for a vanity case substantially as shown and described.

OSSIP J. WALINSKY.
